UNITED STATES PATENT OFFICE.

AMOS S. HAYDEN, OF HOLBROOK, MASSACHUSETTS, ASSIGNOR TO UNITED SHOE MACHINERY CORPORATION, OF PATERSON, NEW JERSEY, A CORPORATION OF NEW JERSEY.

SHOE-BOTTOM-STAINING MACHINE.

Application filed June 29, 1922. Serial No. 571,713.

To all whom it may concern:

Be it known that I, AMOS S. HAYDEN, a citizen of the United States, residing at Holbrook, in the county of Norfolk and State 5 of Massachusetts, have invented certain Improvements in Shoe-Bottom-Staining Machines, of which the following description, in connection with the accompanying drawings, is a specification, like reference characters on the drawings indicating like parts in the several figures.

The present invention relates to machines 10 for applying blacking and other stains to the bottom-portions of shoes, and especially 15 to the edges thereof.

In an apparatus of this character designed 20 for coating shoe-heels, which is the subject of Patent No. 1,025,523, Furber, May 7, 1912, the application of stain to the work 25 is effected by a rotatable brush operating over the sides of the heels, and by a rotatable, frusto-conical member, the edge of which enters the crease and coats the rand. The stain is supplied from a tank to the 30 crease member, and from this to the brush by a member in the form of a rotatable disk having at one side, adjacent to the periphery, a stain-feeding surface co-operating with the crease member. To understand the 35 effect of the present invention, it should be noted that to provide for the correct coating of the heel-surfaces, the amount of stain delivered to the crease member is controlled by a stripper consisting of a steel screw 40 threaded through the casing of the machine and having its inner end, which presents a plane surface, in proximity and parallel to the feeding surface of the disk. The 45 closeness with which the end of this screw approaches the feeding surface determines the amount of stain carried thereby, and therefore the delivery to the crease member and brush. Since it is desired that there shall always be some feed by the disk in the 50 operation of the machine, it is not intended that the screw-end shall come in contact with the disk. But because the latter may fail to run true, or from too close adjustment by careless operators, the disk, in its rotation, may grind against the screw and wear it. To insure control of the stain over the full width of the feeding surface, the

edge of the screw-end is made to overhang somewhat the periphery of the disk. This end-portion, which is not opposite the feeding surface, does not, of course, wear with the remainder, and may become a projection extending outside the edge of the disk. Then when the operator again turns the screw toward the disk to lessen the feed, the projection, revolving opposite a part of the feeding surface, prevents the stripping action over the associated worn portion, which may deliver too much stain to the applying members and produce unsatisfactory results. 55 Correction of this defect has involved a truing of the end of the screw in a lathe. Such a course is necessary to obtain a stain-controlling surface at right angles to the axis of the screw, and therefore parallel to 60 the feeding surface. Grinding off the screw is not sufficiently accurate; an inclination to the axis might be produced which would cause lack of uniformity in stripping. Shoe-shops are not ordinarily equipped for such 65 a turning operation, either as to tools or machinists. In fact, there is rarely any one in such a manufacturing establishment who 70 knows of the causes of the trouble. It has been the custom to call upon the makers of the staining machine. By them a skilled man may be sent, who seeks a machine-shop, 75 if necessary, and performs the truing operation. Experience shows that the expense of this procedure may in some instances approach \$100.

An object of the present invention is to provide an arrangement whereby, if the stain-controlling member comes in contact with the feeding means and its end is thereby worn out of true, the defect may be corrected without removing the controlling member from the machine; without the exercise of skill on the part of the operator; and even without the knowledge of the operator of how the change is being effected. This object I accomplish by the association of such elements that the one causing the departure from the normal conditions brings about their restoration during an adjustment which may be a continuation of or similar to that causing the trouble.

A particular application of the invention is illustrated in the accompanying drawing,

Fig. 1 being a perspective view of a portion of a heel-blacking machine having my improved controlling member;

Fig. 2, a top plan view thereof;

5 Fig. 3, a perspective view of the end-portion of my improved stripping member after it has been subjected to wear;

10 Fig. 4, a detail in vertical section, illustrating the action of the disk upon the stripping member to cause such wear; and

Fig. 5, a similar view, in which appears the relation of the parts during the correction for wear.

The staining apparatus disclosed is that 15 of the type known in the art as the Crest heel blacking machine model B, and, as far as its general structure is concerned, is as shown and described in the patent previously referred to. The more essential elements appear as supported upon a column 20 above a staining receptacle 12, and consisting of a rotatable rand-engaging member 14 having an edge 16 arranged to enter the crease of a shoe and guide it, while 25 also applying stain to the rand; a rotatable member 18 running in the stain contained in the receptacle 12 and having a feeding surface 20 upon one face delivering the elevated stain to the crease member; and a rotatable brush 22 receiving stain from the member 14 and spreading it upon the curved 30 side wall of the heel.

Threaded through the frame of the machine, with its axis alined with and at right 35 angles to the feeding surface 20, is a metal rod 24 furnishing a portion of a stain-controlling member and having a hand-wheel 26 fixed upon its outer end, by which it may be turned to advance its inner extremity to 40 ward or withdraw it from the feeding surface. At this inner end of the rod is a bore or recess 28, preferably concentric with the axis, to receive the active controlling element. This consists of a plug or cylindrical member 30 fitting tightly within the 45 recess, so that it is held against displacement therefrom, and presenting to the feeding surface 20 a plane face parallel to said surface and extending radially of the feeding disk somewhat beyond its edge. The member 30 is of some material substantially softer than the disk, which is usually of cast iron. I prefer to employ for this purpose a fine-grained wood, as maple. For the reasons which have already been indicated, the 50 controlling member 30 may, in the use of the machine, become worn opposite the disk at 32. This results in the formation of a projection 34 where the member overhangs the edge of the disk; see Fig. 4 of the drawings. As the use of the machine proceeds, the space between the controlling member and disk at 32 may grow too great, so that 55 an excessive amount of stain is supplied to the applying members. Then when the op-

erator turns the rod 24 in a clockwise direction to advance the end and reduce the space, the projection 34 will come opposite the disk (Fig. 5). This revolution of the portion 34 is permitted, in spite of the extension over the disk-edge, by irregularities in the latter and lateral play in the disk, it being noted that the length of this portion 34 has been exaggerated in the drawings to make the relation clearer. An amount 60 as small as one-sixty-fourth of an inch will disturb the controlling effect. When the projection 34 is alined with the feeding surface 20, which now bears against it, the rotation of this disk will at once begin to 65 wear away the comparatively slender portion. The rapidity of this action is increased, because the operator now finds that there is still too much stain being fed as a result of the holding away of the major 70 controlling surface 32 from the feeding surface by the projection 34. Consequently, as he continues to turn the rod, the portion 34 is reduced until it is brought to the plane 75 of the surface 32. Now the operator discovers that the feeding surface is being 80 stripped clean, and that he is getting too little stain, and turns the rod 24 anti-clockwise. As the controlling surface of the member 30 is now true, a satisfactory 85 adjustment by movement in this direction may 90 promptly be obtained.

The entire operation, it should be observed, is accomplished rapidly and without 95 skill or the exercise of judgment on the part 100 of the operator, beyond that necessary to determine the amount of stain which he wishes to feed. The adjustment having been made, it will be maintained until disturbed by some of the extraordinary circumstances 105 of maladjustment or machine-defects, since otherwise there is between the parts no wearing contact.

Having described my invention, what I 110 claim as new and desire to secure by Letters Patent of the United States is:

1. In a shoe-bottom-staining machine, an applying member, feeding means including a rotatable disk, and a feed-controlling member having a portion of wood co-operating 115 with the feeding surface of the disk and extending beyond the periphery thereof.

2. In a shoe-bottom-staining machine, an applying member, a metal feeding member therefor, and a wooden stripper co-operating 120 with the feeding member.

3. In a shoe-bottom-staining machine, a stain-applying member, a rotatable feeding member therefor having a stain-carrying surface at its edge-portion, a stripper mounted to turn about an axis extending substantially at right angles to the carrying surface, co-operating at its extremity with said surface and projecting beyond the edge of the feeding member, such co-operating por- 125 130

tion being of material softer than the feeding member, and means arranged to permit the stripping surface to be advanced toward the feeding member.

5. 4. In a shoe-bottom-staining machine, a stain-applying member, a rotatable feeding member therefor having a metal stain-carrying surface at its edge-portion, a screw

mounted for adjustment by its rotation toward and from the carrying surface, and a wooden plug mounted in the end of the screw, co-operating with the carrying surface and projecting beyond the edge thereof.

In testimony whereof I have signed my name to this specification.

AMOS S. HAYDEN.
